CLAIM

The ornamental design for a hybrid cable guard slide for compound archery bows, as shown and described.

DESCRIPTION

FIG. 1 is a topside, perspective view of the hybrid cable guard slide for compound archery bows viewed obliquely from above.

FIG. 2 is an end perspective view of the hybrid cable guard slide viewed obliquely from below.

FIG. 3 is a front side perspective view of the hybrid cable guard slide viewed obliquely from below.

FIG. 4 is a front side perspective view of the hybrid cable guard slide turned obliquely to the left below.

FIG. 5 is front perspective view of the hybrid cable guard slide.

FIG. 6 is a back perspective view of the hybrid cable guard slide.

FIG. 7 is a perspective view of a proximate end of the hybrid cable guard slide.

FIG. 8 is a perspective view of the opposite or distal end of the hybrid cable guard slide.

FIG. 9 is a top plan view of the hybrid cable guard slide.

FIG. 10 is a bottom plan view of the hybrid cable guard slide; and,

FIG. 11 is an bottom side perspective view of the hybrid cable guard slide viewed obliquely from below.
